UNITED STATES PATENT OFFICE.

JOSEPH OETTINGER, OF MISSOULA, MONTANA.

TYPE-WRITER ATTACHMENT.

No. 871,815.

Specification of Letters Patent.

Patented Nov. 26, 1907.

Application filed January 21, 1907, Serial No. 353,279.

To all whom it may concern:

Be it known that I, JOSEPH OETTINGER, of Missoula, in the county of Missoula, State of Montana, have invented certain new and useful Improvements in Type-Writer Attachments, of which the following is a specification.

The object of my invention is to produce a device adapted to be attached to a typewriter designed and adapted for manifolding without handling the carbon paper or the paper upon which the copy is printed. The end referred to is accomplished by the employment of a continuous roll of copying paper in connection with a copy producing platen. Devices hitherto employed for a similar purpose have been more or less complicated and expensive.

My present invention is intended, in respect to the class of devices mentioned, to combine complete practical efficiency with simplicity and cheapness.

In the accompanying drawings, which form a part of this application, Figure I is a front elevation of a portion of a No. 6 Remington typewriter, shown merely by way of illustration, together with my invention operatively applied thereto. Fig. II is an end elevation of the subject matter of Fig. I, 30 illustrating the operation of my invention.

Referring to the numerals on the drawings, 1 indicates one terminal bracket support and 2 another. Each is adapted to be secured, as by screws 3, to a frame 4 of the typewriter. These supports are substantially identical one with the other, and both are provided with coaled journal bearings 6, in which an axle 7 is rotatably supported.

8 indicates a platen of the machine, 40 mounted in any usual or preferred manner in the frame 4, the typewriter illustrated being a No. 6 Remington, but that is merely selected for the purposes of explication as my invention is applicable to any form of typewriter, with such structural changes as the form of the typewriter in question may require, the principle of my invention continuing unchanged independent of structural details.

50 The bracket supports 1 and 2 are provided with slots or slip bearings 10 and 11, respectively, which are adapted to accommodate, and preferably to removably accommodate, a stationary knife, which preferably consists 55 of a blade 12 and a back or stiffener 13. The stiffener may be made in tubular form, bent

to engage opposite sides of the blade and to support it rigidly in position.

An important feature of my invention is found in mounting the knife 12 and the axle 60 7 in parallel relationship and in close contiguity, though preferably the contiguity of those members is not so close as to permit them to touch each other, nor even to permit the knife to touch any roll of paper that 65 may be mounted upon the axle 7.

By reason of the close contiguity of the members 7 and 12, provision of the simplest sort is made for enabling the platen 8 to constitute a direct feed for the copying paper 70 wound in a continuous roll 15 upon the axle 7. The reason is this. The copying paper, passing from the roll 15 around the platen 8 in a loop 16, is drawn up between the knife 12 and the roll 15. By placing the roll and 75 the knife in close contiguity, the paper is caused, in effect, to hug almost the entire periphery of the platen 8, which may, therefore, be depended upon to impart movement to the paper, drawing it off from the roll 15 80 and passing it above the edge of the knife 12 in the usual step by step movement, or other rotative movements of the platen. Moreover, the copying paper is by this means made, in effect, a close fitting covering for 85 the platen, whereby the letter sheets, separate or continuous as preferred, may be employed in connection with my invention for manifolding.

The knife 12 is provided in order that sections of the copying sheet may be severed when, and as often as required, by simply drawing a projecting portion of the sheet across the edge of the knife 12 and tearing it off in the usual manner. In practice the 90 severed portion of the copying sheet would be such as accommodates the copy of the letter or other separate item of written matter. This tearing off of a sheet of copy may be accomplished without interfering 95 with the continued operation of the machine, the line of division between the portion torn off and the copying sheet being conformable to the edge of the knife 12 and well elevated above the line disposed endwise of the platen 100 105 along which the copying sheet leaves the platen and passes up between the knife and the roll 15.

For the purpose of producing impression upon the copying sheet, I provide the platen 110 8 with a carbon covering. It is preferably provided by covering the platen with a close

fitting sleeve of paper or fabric 17, provided with a suitable coating of copying material or carbon.

As often as a key of the machine strikes the 5 face of the platen 8, it will, in addition to its usual function, produce an impression upon the copying sheet that is passed around the platen, by reason of the presence of the carbon coating upon the platen. The copy 10 produced upon the copying sheet is, of course, negative, but it is entirely practicable to render the copy legible, through the employment of paper for the copying roll of sufficient thinness to expose the marks upon 15 it to be read from the other side from that upon which the marks of the carbon copy actually appear.

What I claim is:

The combination with a typewriter frame 20 and a rotative platen, of a pair of terminal bracket supports removably secured to the

typewriter frame at opposite ends of the platen, said supports being provided respectively with a journal bearing and with a slot, a paper-roll-supporting-axle removably mounted in said journal bearings to rotate in a direction the reverse of that of the platen, and a knife removably mounted in said slots, the paper-roll-supporting-axle and the knife being in such close contiguity as 30 to confine the paper, drawn from the paper-roll-supporting-axle and carried about the platen under the knife, in contact substantially with the entire periphery of the platen.

In testimony whereof I have hereunto 35 signed my name in the presence of two subscribing witnesses.

JOSEPH OETTINGER.
